UNITED STATES PATENT OFFICE.

WILLIAM A. PITTS, OF NEW YORK, N. Y.

IMPROVEMENT IN LIGHTING GAS BY ELECTRICITY.

Specification forming part of Letters Patent No. 139,811, dated June 10, 1873; application filed February 5, 1873.

To all whom it may concern:

Be it known that I, WILLIAM A. PITTS, of the city, county, and State of New York, have invented a certain new and useful Improvement in Lighting Gas by Electricity; and I do hereby declare that the following is a full, clear, and exact description of the same, sufficient to enable those skilled in the art to make and use the invention, reference being had to the accompanying drawing, in which—

Figure 1 represents a side view, showing my invention applied to a gas-fixture. Fig. 2 is a top view of the attachment to the stop-cock of said fixture.

This invention relates to an apparatus for lighting gas by electricity, which is so constructed and arranged that the circuit is closed for creating the electric spark by the movement of the cock in turning on the gas. This result being accomplished, the conductor of electricity or igniting finger is thrown out of action for breaking the circuit.

The invention consists in applying to an ordinary cock for regulating the admission of gas to a burner, a pair of pivoted arms or cranks, arranged on a disk or washer applied to said cock, and connected by a non-conducting cord with a pivoted or vibrating finger or wire, which is situated in close proximity to the burner and connected with one of the poles of a galvanic battery, so that when the cock is turned to admit the gas to the burner said vibrating finger will be brought in contact with the tip of the burner or termination of the opposite pole of the battery, thus creating an electric spark for igniting the issuing jet of gas, after which the circuit is immediately broken, and the igniting or circuit-breaking finger is removed from the burner by the action of a spring.

A in the drawing may represent a gas-fixture, chandelier, bracket, drop-light, or other analogous fixture to which my apparatus for lighting gas is to be applied. The fixture or gas-pipe is provided as usual with a stop-cock, P, and key B, and to the upper end of said cock is attached a disk or washer, C', as shown.

A movable crank-arm, C², pivoted or hung loosely on a central screw, projecting from said disk C¹, carries a second pivoted or loose arm, C³, which is, by means of a cord, I, of silk, cat-gut, or other non-conducting material, connected to a vibrating finger or wire, F, arranged in proper relation to the tip D^x of the burner, as shown.

E is a bracket or insulating collar of wood, ivory, vulcanite, or other suitable material, on which the vibrating finger is arranged for maintaining the electric circuit intact. The gas-pipe or fixture is, by means of a wire, connected with one of the poles of a galvanic battery, and from the opposite pole extends a wire, K, which is carried to the finger of the burner, as shown.

In the operation of lighting gas the cock P is turned nearly to its full extent for permitting the flow of gas to the burner. This causes a stud, S, on the disk or washer of the stop-cock to move the crank-arm C² or its pivot beyond its center, and, through the medium of the arm C³ and cord I, to bring the curved or vibrating finger or wire F in contact with the tip of the burner, thus closing the electric circuit and creating a discharge of sparks which serve to ignite the gas issuing from the burner.

During the igniting operation, which is almost instantaneous, the stop-cock is turned open to its full extent, causing the crank-arm to pass beyond its center, when the same is immediately returned to its normal position for removing the igniting-finger from contact with the burner, in order to break or interrupt the electric circuit, by means of a spiral or other suitable spring, H, arranged in proper relation to the circuit-breaking or igniting finger, as shown.

From the above description it will be perceived that means are provided for lighting gas by means of electricity, with celerity and precision, with a simplified arrangement of parts, not liable to become deranged or to be rendered inoperative.

What I claim as my invention, and desire to secure by Letters Patent, is—

1. The method of lighting gas by means of an electric circuit-breaking and breaking de-

vice, arranged in proper relation to the burner, and combined with a stop-cock for enabling the circuit to be closed for igniting the gas by the opening movement of said cock, as herein shown and described.

2. The combination of the stop-cock attachment C¹, and the insulating-string I, with bent wire or igniting-finger F, spring H, and insulator E, for the purpose herein set forth.

3. The disk C¹ provided with crank-arms C²C³, and with studs S S, combined with a stop-cock and circuit-closing device, for operation in the manner set forth.

WILLIAM A. PITTS.
